Primary Examiner — Kevin K Rudzinski*Assistant Examiner* — Richard E Yenchesky(74) *Attorney, Agent, or Firm* — Kattina V Barsik, Esq.(57) **CLAIM**

The ornamental design for a paint pourer, as shown and described.

DESCRIPTION

FIG. 1 is a right side elevation view of a paint pourer showing my new design;

FIG. 2 is a front elevation view thereof;

FIG. 3 is a rear elevation view thereof;

FIG. 4 is a right side elevation view of the paint pourer attached to a paint can of one size; and,

FIG. 5 is a right side elevation view of the paint pourer attached to a paint can of another size.

Broken lines in the drawings depict portions of the paint pourer or environment that form no part of the claimed design.
